UNITED STATES PATENT OFFICE.

ELBERT E. MUNGER, OF SPENCER, IOWA.

LIFTING DEVICE FOR HOSPITAL-BEDS.

SPECIFICATION forming part of Letters Patent No. 658,217, dated September 18, 1900.

Application filed April 11, 1900. Serial No. 12,434. (No model.)

To all whom it may concern:

Be it known that I, ELBERT E. MUNGER, a citizen of the United States, and a resident of Spencer, in the county of Clay and State 5 of Iowa, have invented a new and Improved Lifting Device for Hospital-Beds, of which the following is a full, clear, and exact description.

My invention relates to beds for sick and 10 invalid persons, and is adapted for use especially in hospitals, sick-rooms, and the like.

The object of the invention is to provide a 15 simple and efficient device for lifting the patient off the mattress whenever it is desired to change the latter or the bedding or for other purposes.

To this end the invention consists in certain features of construction and combinations of parts, as will be fully described hereinafter, and particularly pointed out in the appended claims.

Reference is to be had to the accompanying drawings, forming a part of this specification, in which similar characters of reference indicate corresponding parts in all the views.

Figure 1 is a perspective view of a bed having my improvement applied thereto. Fig. 2 is a cross-section thereof, and Fig. 3 is an end view showing a slightly-different construction.

The bed proper may be of any suitable construction, comprising head-posts A, foot-posts B, side rails C, and end rails D. A mattress E of any suitable construction is 35 placed on the bed, and over said mattress are passed in a transverse direction under the patient strips P of canvas, duck, or like fabric or material quilted up to a point near the edges. On the ends of the said strips are 40 secured apertured straps P', adapted to be hooked upon buttons or pins Q', secured on shafts Q, mounted to turn in suitable bearings formed on the free ends of arms Q², hinged to the side rails C of the bed-frame.

45 The arms Q² are normally in a lowermost position and rest at their ends on collars A³ and B³ on the head-posts A and foot-posts B, respectively, and when the arms Q² are swung into an uppermost position they rest against 50 collars A⁴ and B⁴, likewise on the head-posts A and the foot-posts B, respectively. When in this uppermost position, the shafts Q are a

distance above the top surface of the mattress E, so that the strips P extend downward from the shafts under the patient. On the foot 55 ends of the shafts Q are secured sprocket-wheels R R', which, as shown in Fig. 1, are connected with each other by a crossed sprocket-chain R², so that when one shaft is rotated a rotary motion is given to the other 60 shaft, but in a reverse direction. In this construction there is also secured on the end of one of the shafts Q a crank R³, which when turned by the operator causes a simultaneous rotation of the shafts Q, as described, so that 65 the strips P are first wound up and then the ends of the strips P, whereby the said strips gradually assume a horizontal position, thus lifting the patient from the mattress to allow of removing the mattress or changing the 70 bed-linen beneath the patient. Also by placing the strips beneath the patient at suitable distances easy access is obtained to any portion of the posterior part of the body, thereby facilitating the treatment and care of sores 75 or injuries or other conditions which make it necessary to have access to the back. When the strips P have assumed a horizontal position, then the two runs of the sprocket-chain R² are locked together at their point 80 of crossing by a suitable key R⁴ to prevent accidental turning of the shafts Q during the time the patient is suspended on the strips P. The collars A² A³ and B² B⁴ are made of leather or other suitable material to 85 form suitable rests for the shafts Q, to prevent marring the bed-posts, and to prevent undue noise when the shafts are moved into a lowermost or uppermost position. When the shafts Q are swung into an uppermost position, an upwardly-arched transverse brace 90 Q³ is engaged at its forked ends by the central portions of said shafts or by the central arms Q² to prevent the shafts from bending when loaded with the patient, as above described. In some cases it may be advantageous to provide for an independent adjustment or rotation of the shafts Q, and for this purpose a crank Q⁴ may be secured to each shaft, with a pawl Q⁵ engaging a ratchet-wheel 95 Q⁶ to lock the shaft.

Having thus described my invention, I claim as new and desire to secure by Letters Patent—

1. A bed having a frame, arms hinged on said bed-frame, shafts journaled in said arms, and adapted to rest against the head and foot of the frame, transverse supporting-strips connected with said shafts to wind thereon, and means for rotating said shafts to wind up or unwind said strips, the said means comprising sprocket-wheels on the shafts, a sprocket-chain connected with the sprocket-wheels, and a crank on one of said shafts, substantially as shown and described. 35

2. A bed having a frame, arms hinged on said bed-frame, shafts journaled in said arms, and adapted to rest against the head and foot of the frame, supporting-strips connected with said shafts to wind thereon, means for rotating said shafts to wind up or unwind said strips, the said means comprising sprocket-wheels on the shafts, a sprocket-chain connected with the sprocket-wheels, a crank on one of said shafts, and a removable brace for the said shafts when in an elevated position, substantially as shown and described. 40

3. A bed having a frame, arms hinged on said bed-frame, shafts journaled in said arms, and adapted to rest against the head and foot of the frame, transverse supporting-strips connected with said shafts to wind thereon, means for rotating said shafts, to wind up or 45 unwind said strips, the said means comprising 50

ing sprocket-wheels on the shafts, a sprocket-chain connected with the sprocket-wheels, a crank on one of said shafts, and means for locking the shafts against accidental turning, substantially as shown and described. 55

4. The combination with a bed having side rails, of arms pivoted to said side rails, shafts journaled in said arms, flexible strips adapted to connect said shafts, and means for rotating the shafts. 60

5. The combination with a bed, of arms pivoted thereto upon pivots extending lengthwise of the bed, longitudinal shafts journaled in said arms, flexible strips adapted to connect said shafts, and means for rotating the shafts. 65

6. The combination with a bed, of arms pivoted thereto upon pivots extending lengthwise of the bed, longitudinal shafts journaled in said arms, flexible strips adapted to connect said shafts, means for rotating the shafts, and means for locking them against rotation. 70

In testimony whereof I have signed my name to this specification in the presence of two subscribing witnesses.

ELBERT E. MUNGER.
